UNITED STATES PATENT OFFICE.

JOHN C. KUPFERLE, OF ST. LOUIS, MISSOURI.

FIRE-HYDRANT.

SPECIFICATION forming part of Letters Patent No. 535,910, dated March 19, 1895.

Application filed August 2, 1894. Serial No. 519,230. (No model.)

To all whom it may concern

Be it known that I, JOHN C. KUPFERLE, of St. Louis, Missouri, have made a new and useful Improvement in Fire-Hydrants, of which 5 the following is a full, clear, and exact description.

The improvement relates to the waste of the hydrant; and it consists in the means hereinafter set out and claimed, reference being 10 had to the annexed drawings, making part of this specification, and in which—

Figure 1 is in part a vertical cross section of the body of a hydrant containing my improvement, and in part, a view in perspective 15 of those parts with which my improvement is most directly connected, the view being upon a reduced scale and the main valve being shown seated and the waste open. Fig. 2 is a vertical section on a larger scale of the lower 20 end or foot of a hydrant, being the portion with which my improvement is immediately connected. In this view also, the valve is shown seated and the waste open. Fig. 3 is a similar view, except that the main valve 25 and parts thereto attached are shown in perspective, and that the main valve is unseated and the waste closed, and Fig. 4 is a vertical cross section of an improved rubber packing used by me, and through which the extension 30 of the stem of the main valve is intended to pass.

The same letters of reference denote the same parts throughout the several views.

The valve A, seats at a, against the pressure, the water entering through the inlet B 35 into the chamber C in the lower end or foot D of the hydrant, and thence, when the valve A is unseated, passing upward past the valve into the upper part of the hydrant, D', whence 40 it is discharged in the ordinary manner.

As the improvement does not depend for its operation, upon any special construction at the upper end of the hydrant, that part need not be specially described.

45 The main valve stem E extends downward below the valve A. Its extension is hollow (Fig. 2). It is perforated both above the main valve and near the lower end of its extension e. The perforations above the valve are lettered e' and those below it e². The extension passes through a central perforation f in a packing F, preferably cone shaped as shown

in Fig. 4 and provided with a thin lip f', at its upper end and the flange f² at its lower end. I prefer to form this packing of rubber. 55 Soft rubber answers the purpose best. The packing F is contained within the tubular plug G. It preferably rests upon an annular rib g, preferably held in place by means of a sleeve G' screwed into the top of the plug G 60 and bearing upon the flange f² of said packing.

In the form of my improvement shown in the drawings there is a chamber g² below the rib g, and passages g³ g⁴ are provided for the 65 escape of water therefrom to without the hydrant. The plug G and the sleeve G' are both preferably perforated so as to permit of a free circulation of water around the packing F, and allow any sediment which might otherwise accumulate around the packing, to escape. 70 The perforations in the plug G are lettered g⁴, and those in the sleeve G' are lettered g⁵.

When the main valve A is seated, the portion of the stem containing the perforations e², extends below the packing F, as appears in Fig. 2. When the parts are in that position there is a free passage for any waste water left in the upper part (D') of the hydrant, through the perforations e', and the stem extension e, the perforations e², the chamber g² and the passages g³ to without the hydrant. When on the other hand, the main valve A is lifted off its seat, as shown 85 in Fig. 3, the portion of the valve stem (e) containing the perforations e², is sufficiently elevated to bring said perforations within the packing F. As soon as this takes place they are closed by the packing and the escape of 90 water through them prevented. Thus the waste is always open when the valve is closed, and is closed by the opening of the main valve.

The packing F devised by me is very efficient in making a water tight joint by reason of its elasticity and its form. The pressure of water upon its sides and especially upon its lip f assists in keeping it tight.

In case the valve A, or its stem E, needs repairing the top of the hydrant may be taken off and the valve lifted out by its stem. In such cases the packing F is left in place. The lower end e³ of the stem extension e is pref-

erably conical or pointed so as to permit of its easy insertion into the central perforation f of the packing F , and when the main valve and its stem have been taken out of the hydrant, the stem extension e can be inserted in its packing without difficulty when the valve is replaced.

It is believed that the special form of packing (F) which I have described will last as long as a hydrant. In case it should become desirable to remove such a packing however the sleeve G' , may be unscrewed and the packing lifted out without difficulty and a new one inserted.

Hydrants embodying my invention are cheap, efficient, simple and very durable.

The perforations e' , e^2 , g^4 , and g^5 are respectively preferably two or more in number but a single one of each may be used.

I claim—

1. The combination of the tubular plug G having one or more perforations g^4 , the perforated elastic packing F , having the flange f^2 resting upon a support formed in said plug G , and a sleeve G' having one or more perforations g^5 , substantially as described.

2. The combination of the tubular plug G having one or more perforations g^4 , the soft rubber, cone shaped packing F , having a lip f' and a flange f^2 , a support for said packing and a sleeve G' having one or more perforations substantially as described.

3. The combination in a hydrant, of the valve A having the seat a , the hollow stem extension e , whose interior is connected with the space above the valve seat by a passage e' ; the tubular plug G containing one or more lateral perforations g^5 , and a support for a packing; a rubber packing F , having the central perforation f and the lip f' , the sleeve G' having one or more perforations g^5 , and one or more lateral openings e^2 in said valve stem extension, open when said valve is seated and closed when it is unseated, substantially as described.

Witness my hand this 31st day of July, 1894.

JOHN C. KUPFERLE.
